UNITED STATES PATENT OFFICE.

GEORGE R. HUNT, OF KIRWIN, KANSAS.

FORCE-PUMP.

SPECIFICATION forming part of Letters Patent No. 239,957, dated April 12, 1881.

Application filed December 23, 1880. (No model.)

To all whom it may concern:

Be it known that I, GEORGE R. HUNT, of Kirwin, in the county of Phillips and State of Kansas, have invented certain new and useful 5 Improvements in Force-Pumps; and I do hereby declare that the following is a full, clear, and exact description of the invention, which will enable others skilled in the art to which it appertains to make and use the same, reference 10 being had to the accompanying drawings, which form a part of this specification.

Figure 1 is a perspective view. Fig. 2 is a vertical sectional view, and Fig. 3 is a view of the valve or piston detached.

15 Corresponding parts in the several figures are denoted by like letters of reference.

This invention relates to double-acting force-pumps; and it consists in certain improvements in the construction of the same, which 20 will be hereinafter fully described, and particularly pointed out in the claim.

In the drawings hereto annexed, A represents the pump-cylinder, which is closed at its lower end, and provided at its upper end with 25 a detachable but close-fitting cover, B. C is the water-pipe, which is arranged parallel to and connected by passages D D with the upper and lower ends of the cylinder. Near the upper end of the water-pipe is pivoted a lever, 30 E, carrying at one end a bail, F, by means of which the pump-piston is operated.

The piston or valve G consists of a rod or stem, H, carrying at each end a plunger, I. The plungers I are provided with openings J, 35 ground to form seats for the buttons K, one of which is formed or secured upon each end of the valve-stem. The plungers are provided with arms L, connected by cross-bars M, passing through and sliding in slots N in the valve- 40 stem, to which the plungers are thus secured in such a manner that they may slide a short distance longitudinally in relation to the valve-stem. The latter is provided at its center with a transverse cross-bar, P, extending out 45 through vertical slots or openings O in the sides of the cylinder, said slots O being of sufficient size to admit the water freely into the

cylinder. The arms of the operating-bail are pivoted to the outer ends of the cross-bar P.

From the foregoing description, taken in 50 connection with the drawings hereto annexed, the operation and advantages of my invention will be readily understood.

On the downstroke of the piston the stem closes the opening J in the lower plunger, 55 while the opening in the upper plunger is open for the admission of water into the upper part of the cylinder. On the upstroke the position of the stem is reversed, thus opening the ori- 60 fice in the lower plunger for the admission of water into the bottom of the cylinder, while the water contained in the upper portion of the same is forced through passage D into the conduit-pipe. In the passages D suitable valves are arranged opening into the pipe C. 65

The pump-cylinder is in practice arranged in the bottom of the well, upon a suitable foundation.

My improved pump, as will be seen from the foregoing, is simple in construction, durable, 70 and easily operated. Owing to the absence of valves in the cylinder, it is not liable to get out of order or to become choked up by obstruc- tions of any kind.

Having thus described my invention, I claim 75 and desire to secure by Letters Patent of the United States—

In a double-acting force-pump, the combination of the stem H, having end buttons, K K, and elongated slots N N near the ends thereof, and the plungers I I, provided with arms L L, connected together and to said stem by cross-bars M M, passing through said slots N N, whereby said plungers are adapted to move on said stems substantially in the manner 85 herein shown and described.

In testimony that I claim the foregoing as my own I have hereto affixed my signature in presence of two witnesses.

GEORGE R. HUNT.
